UNITED STATES PATENT OFFICE.

GEORGE E. SIPHERD, OF GALESBURG, ILLINOIS.

BOOT AND SHOE CLEANER.

965,029.

Specification of Letters Patent. Patented July 19, 1910.

Application filed December 3, 1909. Serial No. 531,227.

To all whom it may concern:

Be it known that I, GEORGE E. SIPHERD, a citizen of the United States, residing at Galesburg, in the county of Knox and State 5 of Illinois, have invented a new and useful Boot and Shoe Cleaner, of which the following is a specification.

My invention relates to boot and shoe cleaners.

10 The principal object of the invention is to provide a novel device of the character recited which is effective, durable, simple, and economic of manufacture; which is provided with a clean-out trough, and in 15 which that part which is most subjected to wear may be readily replaced when worn, without removal or disturbance of the other parts.

20 Other objects will be in part obvious and in part pointed out.

To the end of carrying out these objects the invention consists in constructions, combinations, and arrangements of parts hereinafter described and made the subject matter 25 of claims hereto appended.

A device embodying the preferred constructive form of, and showing the arrangement and mutual relationship of the parts forming the subject matter of my improvements, is illustrated in the accompanying drawings, in which:—

Figure 1 is a top plan; Fig. 2, a front elevation; and Fig. 3, an end elevation seen from that end of the device at which the 35 brush is located.

In said drawings the same reference numeral indicates the same part wherever applied.

2 represents a base, or base-plate, preferably of sheet metal, the rear portion of 40 which is bent or flanged upwardly, primarily to provide one member of a clean-out trough 17. This flange however serves a triple function—it serves also as a cleaning bar 45 when the device is used from the rear side, and as a support for a bent plate or bar 4, one end of which is fixed thereto by a rivet 5. One end portion 6 of the plate 4 lies along and perpendicular to a portion of the 50 base 2, is then bent at a right angle to form the scraper portion 7, thence again bent at a right angle to provide a portion 8 to which one end of the hereinafter described brush is secured, and finally bent outwardly 55 at a right angle to provide an extension 9 to which one side of the brush is secured.

If preferred, the portions 8 and 9 may be dispensed with and the scraper bar 7 be continued or extended along one side of the brush as shown by dotted lines at Fig. 1, 60 and secured thereto by screws, as shown.

The cleaning brush, which may be of any desired and suitable construction, is shown as being made after the usual fashion or manner of such articles and comprises a 65 back 10, bristle-plate 11 and bristles 12. Screws 13 are threaded through the base 2 and into the back 10. A screw 14 is threaded through the portion 8 of the bent bar 4 and into the back 10, and screws 15 70 through the portion 9 and also into the back 10. It will be evident that the screws 13 hold the brush rigidly and securely but removably in place, and that, thus held, the screws 14 and 15 hold the scraper bar from 75 movement.

The portions 6, 7, and 8 of the bar 4 form a dirt-receptacle 16, while the brush-back and flange 3 form the clean-out trough 17 hereinbefore described. 80

When used from in front the operator will hold the device from movement by placing one foot and thereby his weight on the free or unoccupied side of the base moving the bottom portions of the sole and heel of the 85 shoe being cleaned over the bar 7, whereupon said portions as well as the "upper" may be thoroughly freed from dirt etc. by moving them over the upstanding bristles of the brush, which bristles it will be noted rise 90 well above the metallic portions of the device.

When used from the rear side the device is generally secured to a porch floor or walk by screws (not shown) passed through 95 the apertures 18 in the base plate, though it may be held by the shoe not being cleaned. The other shoe is then to be drawn across the bristles to remove all dust and accumulations, while the flange 3 will at the same 100 time and by the same movement remove all hardened accumulations. The combination or mutual coöperation of the bristles and flange thus perfectly cleaning the shoe at a single 105 operation.

The advantages of the invention will be apparent and the operation understood from the foregoing description, it being particularly noted that various changes may be made in the details of construction and arrangement of the parts without departing materially from the general idea involved. 110

Having thus described the nature of the invention and the best means I know for carrying it into effect, I claim as new and desire to secure by Letters Patent the following, to-wit:

- 5 1. A device of the nature described comprising a base provided with a flange along its rear edge, a bent scraper-bar secured at one of its ends to said flange, and a brush secured to said base, the other end of said scraper-bar secured thereto.
- 10 2. A device of the character described

comprising a base including a flange, a brush secured to said base, spaced from said flange, said flange and brush constituting a clean-out trough, and a bent plate secured at its ends to said flange and brush, said flange and plate constituting a dirt receptacle.

In witness whereof I hereunto affix my signature this 29th day of November, 1909.

GEORGE E. SIPHERD.

In presence of—
CHAS. S. HARRIS,
MYRLE NORTON.
